TOWEL SUPPORT

Filed August 10, 1925

FIG. 1.

FIG. 2.

INVENTOR
Malcolm M. McKenzie
BY *White & Frost*
his ATTORNEYS

UNITED STATES PATENT OFFICE.

MALCOLM M. MCKENZIE, OF SAN FRANCISCO, CALIFORNIA.

TOWEL SUPPORT.

Application filed August 10, 1925. Serial No. 49,408.

This invention relates to means for supporting a towel and the like on patients in medical and dental offices to prevent the soiling of their garments and the dropping of materials employed during operations, such as for example on the nose, throat or teeth, on the patients and the floor. The support embodying my invention has been found of particular value in connection with dental work where plaster casts are formed in which case there is always an excess of material present that must be removed. In present practice, bibs of various types are used which are simply secured around the neck of the patient and hang flat over his chest, and materials dropping from the mouth of the patient simply roll to his lap or to the floor.

It is an object of the present invention to provide a support for towels, which may be readily placed in proper position on the patient and readily removed upon completion of the operation.

Another object of my invention is to provide a device of this character in which towels may be supported so as to prevent any matter or material from soiling the garments of the patient and to confine all such matter or material within the towel.

A further object of my invention is to provide means for supporting a towel covering the chest of the patient and held so as to form a basket or receptacle to catch matter dropping from the patient's mouth.

It is a still further object of my invention to provide a support of the character indicated on which clean towels may readily be placed, and soiled towels readily removed with such matter and materials deposited thereon either by the patient or professional attendant gathered in the folds thereof so as to prevent any dropping of the same on the patient or floor.

The invention possesses other advantageous features, some of which with the foregoing will be set forth at length in the following description where I shall outline in full that form of the invention which I have selected for illustration in the drawings accompanying and forming part of the present specification. In said drawings I have shown but one form of my invention but I do not desire to be limited thereto, as the invention as expressed in the claims may be embodied in a plurality of other forms.

Referring to the drawings:

Figure 1 is a perspective view of a holder embodying my invention, with the open ends shown locked together as when in use, and with said ends shown in open position in dotted lines to indicate their position before the support is attached on the patient; and

Fig. 2 is a perspective view illustrating the device with the towel thereon in operative position on a patient.

My invention comprises a frame 1 made of suitable light material, preferably wire, and obviously may assume many forms. In the present form illustrating an embodiment 70 of my invention, I have provided two vertical wires 2 and 3, with their lower ends 4 and 5 curved upwardly on the front side of the holder. Preferably, the curved portions 4 and 5 are parallel. The ends of the 75 portions 4 and 5 are connected by a horizontal wire 6, which is preferably welded or soldered thereto. The ends 7 and 8 of the wire 6 extend slightly beyond the portions 4 and 5 respectively and are curved 80 backwardly to the upright wires 2 and 3 to which the same are also fixed in any suitable manner. The wires 2 and 3 are secured together by a wire 9, preferably at their curved portions in order to make the 85 holder more rigid. The upper ends 10 and 11 of the vertical wires 2 and 3 are bent back slightly as indicated at 12 and 13 so as to form a rest on the shoulders of the patient and are provided with hooks 14 and 15 respectively. Suitable clasps or grips 16 and 17 are provided on the horizontal rod 6 adjacent the ends of the portions 4 and 5 of the wires 2 and 3. Similar clasps 95 18 and 19 are also provided on the wires 2 and 3 adjacent the bent portions 12 and 13 thereof.

In operation, the frame 1, with the hooks 14 and 15 disengaged as indicated in dotted lines in Fig. 1, is placed on the chest of the patient with the curved portions 12 and 13 resting on his shoulders. The hooks 14 and 15 are then engaged as shown in Fig. 1, the same being held together by the spring action of the wires 2 and 3 in a manner readily understood. A towel 20 is then spread over the frame and clamped at its upper edge 21 by the clasps 18 and 19, the portion of the towel between the clasps 18 and 19 covering the chest of the patient, and the free ends resting flat on the upper arm portions of the patient. The lower or op-

posite edge 22 of the towel is engaged by clasps 16 and 17, and the intermediate portion of the towel is pushed downwardly so as to form a receptacle within the curved portions 4, 5, 7 and 8 as shown in Fig. 2.

From this it will be seen that the towel 20 is supported by the frame 1 to cover the patient's garments and in the form of a receptacle or basket. Furthermore, towels 10 may be readily removed and replaced without removing the frame from the patient. It is apparent that additional clasping means may be provided, and that they may be arranged in various positions. Likewise, 15 the several wires may assume many contours and be arranged differently. I therefore do not limit my invention to the particular form of frame shown.

I claim:

20 1. A device of the character described comprising two spaced vertical elements formed with bends to fit the shoulders of the patient and adapted to be connected together adjacent said bends, and formed with 25 upwardly curved portions below and in front of said bends, and a horizontal element connecting the free ends of said curved portions, both ends of which are curved inwardly and secured to the adjacent vertical 30 element.

2. A device of the character described comprising two spaced vertical elements, the upper ends of which are bent to pass over the shoulders of the patient and adapted 25 to be secured together in back of the neck of the patient, the lower ends of said elements being formed with upwardly curved 30 portions in a direction opposite to the upper

bent portions, and an element connecting the lower ends of both of said vertical elements together and each of said ends with an intermediate point of its respective vertical element. 40

3. A device of the character described comprising two spaced vertical elements the upper ends of which are bent to pass over the shoulders of the patient and provided with hooks adapted to lock the same together in back of the neck of the patient, the lower ends of said elements being formed with upwardly curved portions in a direction opposite to the upper bent portions, and an element connecting the lower ends of both of said vertical elements together and each of said ends with an intermediate point of its 45 50 55 respective vertical element.

4. A device of the character described comprising two spaced vertical elements the upper ends of which are bent to pass over the shoulders of the patient and adapted to be secured together in back of the neck of the patient, the lower ends of said elements being formed with upwardly curved portions in a direction opposite to the upper bent portions, an element connecting the lower ends of both of said vertical elements together and each of said ends with an intermediate point of its respective vertical element and means on said last mentioned 60 65 70 element and said two vertical elements adjacent their upper ends for engaging the edges of a towel.

In testimony whereof, I have hereunto set my hand.

DR. MALCOLM M. MCKENZIE.
